Attorneys.

UNITED STATES PATENT OFFICE

2,235,666

FUSE

Theodore Birkenmaier, St. Louis, Mo., assignor to
W. N. Matthews Corporation, St. Louis, Mo., a
corporation of Missouri

Application May 31, 1939, Serial No. 276,523

6 Claims. (Cl. 200—114)

This invention relates to fuses, and with regard to certain more specific features, to automatically releasing fuse switches.

Among the several objects of the invention 5 may be noted the provision of an improvement upon the apparatus shown in United States Patent 2,000,876, dated May 7, 1935, issued to Lester P. Boll et al.; the provisions of simple and more economical apparatus of the class described 10 which is also more positive and reliable in operation; and the provision of apparatus of this class which may be re-fused and operated with more facility. Other objects will be in part obvious and in part pointed out hereinafter.

15 The invention accordingly comprises the elements and combinations of elements, features of construction, and arrangements of parts which will be exemplified in the structures hereinafter described, and the scope of the application of 20 which will be indicated in the following claims.

In the accompanying drawings, in which is illustrated one of various possible embodiments of the invention,

Fig. 1 is a side elevation of the device shown 25 in operating condition, the dotted lines indicating an initial released condition;

Fig. 2 is a view similar to Fig. 1 showing a final released condition;

Fig. 3 is a fragmentary side elevation showing 30 the process of applying a fuse holder assembly to certain fixed supports;

Fig. 4 is a longitudinal section of a fuse holder taken substantially on line 4—4 of Fig. 1; and,

Fig. 5 is a fragmentary view of the lower portions of Fig. 1 but viewed from the opposite side.

Similar reference characters indicate corresponding parts throughout the several views of the drawings.

Referring now more particularly to Fig. 1, 40 there is shown at numeral 1 an insulator held by a support 3. At its upper end the insulator 1 is provided with a conducting clamp 5 for holding a pair of spring conducting arms or cantilever extensions 7. The clamp 5 has attached thereto by means of a connector 9 a line wire 11. The arms 7 are spaced and separated toward their free ends (see Fig. 4). They are held in spaced relationship by a spacing clamp 2. The arms or extensions 7 in effect comprise a springing line 45 terminal. When downwardly tensioned they assume the solid-line position of Fig. 1; otherwise the dotted-line position. They are provided with downwardly-directed cam ends 99 and notches or crimps 103.

50 At the lower end of the insulator 1 is attached

a conducting member 13 which constitutes a lower rigid line terminal. Another line wire 15 is attached by means of a connector 17. This lower, rigid terminal 13 is provided with spaced, forwardly-directed wall portions 19, each formed with a ledge 21 adjacent a wide mouth 23 of a slot indicated in general at 25. Each slot 25 has a downwardly-extending narrow portion 27 and a lower forwardly-directed circular notch 29.

At 31 is indicated in general a fuse holder. 10 This consists of an insulating expulsion tube 33 within which is preferably a horn fibre liner 35. Attached near, but spaced from, the lower end 37 of the tube 33 is a fixed conducting collar 39. Its holding pin is shown at 41. This collar 15 is conducting and constitutes a lower, non-resilient, terminal-engaging element. It carries oppositely located conducting gudgeons 43 and 45, the former being larger than the latter. These gudgeons are located on the same center line, 20 and are each generally circular in form, but include a partial flat 47 or 49, as the case may be.

One side of the sleeve 39 is provided with an eye 51 and an extension 53. The eye 51 is completed by a support 55 upon which is located 25 a manually-operable fuse terminal 57. The extension 53 has pivoted thereto a platen 59 which may swing adjacent the tube end 37. The platen 59 is normally biased away from the lower end of the tube by means of a coil spring 58. A stop 60, cooperating with a notch 62, limits the motion of the platen to the dotted-line position shown in Fig. 5.

Fastened to the upper end of the tube 33, as shown at 64, is a fixed sleeve 63 in which are laterally-located guide slots 65 (Fig. 4).

Slidably mounted for limited movement upon the sleeve 63 is a conducting cap 67, to which are attached shoes 69 which slide respectively in the slots 65. The outside screw fasteners 71 40 for the shoes 69 are removable, as are also the shoes (through openings 70), so that the cap 67 may be applied to and removed from the sleeve 63. Before application of the cap on the sleeve, a compression spring 73 is inserted to react between the top of the sleeve 63 and the top 75 of the cap 67. The cap is flared at the bottom as shown at 77 to provide weather protection.

The upper end of the cap 67 is provided with 50 a threaded inlet 79 so that a fuse link 81 may be threaded therethrough. Its conducting head 83 is adapted to rest upon the edge of the inlet. The threaded cap 85 serves to hold in place the head 83. The cap 67 is also provided with 55

gudgeons 93 which are in the plane of the gudgeons 43 and 45.

The fuse link 81 is provided with an upper leader 87 and a lower flexible leader 89 connected by a fusible section 91. The fusible section 91 is preferably near the upper end of the holder, as shown, though not necessarily so. The lower leader 89 extends from the open end 37 of the tube 33 and around the platen 59 and is connected to the terminal 57. During application of the fuse link, it is pulled down through the tube so as to compress the spring 73 as far as possible and to bias the platen 59 into the position shown in Fig. 1. This draws down 15 the gudgeons 93 of the cap 67 to a position as close as they can approach the gudgeons 43 and 45.

Operation is as follows:

The fuse link 81 is first threaded into the 20 fuse holder through the inlet 79 as above described. The cap 67 is pulled down by means of the fuse link and the latter is fastened at 57 after being threaded over platen 59 to hold up the latter. The fuse holder is then inverted 25 and supported upon the lug 95 of a lineman's stick 97 (see Fig. 3). The lower gudgeons 43 and 45 are then applied to the mouths 23 of the slots 25 with their flats 47, 49 foremost. It will be understood that the respective mouths of the 30 respective slots are wide enough just to slidably accommodate the differently sized gudgeons. This is true of other parts of slots to be described. By means of the differently sized gudgeons, reversal of the fuse holder is prevented during application.

After entering the mouths 23 the gudgeons 43 and 45 slide down the narrower portions 27 to the notches 29.

The fuse holder is then rotated upwardly counter-clockwise to the position shown in Fig. 1. For this purpose the lug 95 may be applied to the eye 101 which is rigidly formed on the sleeve 63. This causes the gudgeons 93 to strike upon about the central portion of the downwardly-directed 45 ends 99 of the spring terminals 7 (see the dotted lines and the arrow in Fig. 1).

As the extension 99 is traversed, the gudgeons 93 force down the arms of the spring terminals 7 and finally seat in notches 103. The induced 50 tension in the terminals 7 tends to pull up the fuse holder, including the gudgeons 43 and 45. Since, however, the gudgeons 43 and 45 have rotated to the position such that the flats 47 are in the notches 29, and since the vertical portions 55 27 of the grooves are too narrow to accommodate the non-flat widths of the lower gudgeons, the latter are locked against withdrawal by means of the pull from the spring terminals 7.

Upon overload, the fuse melts at the fusible 60 section 91. At the time of melting it is under the tension of the spring 73 and of the spring terminals 7. Upon melting, expansion of spring 73 and the rising of spring terminals 7 from the solid-line position to the dotted-line position 65 (Fig. 1) results in the gudgeons 93 being raised. This raises the cap 67 and causes instantaneous separation of the fuse link at the fusible portion. Promptly the platen 59 also springs down to withdraw the lower leader 89 while the generated gases (if any) tend to accelerate the lower leader outwardly. Explosive gases generally form upon the heavier overloads, but it is to be understood that the device is effective in the absence of explosive action, such as in the case 70 of so-called dragging overloads.

After the raising action of the spring terminals 7 has been exhausted, the spring 73 follows up the action so as to hold the gudgeons 93 clear of the notches 103, as shown by the dotted lines in connection with the fuse holder in Fig. 1. 5 Thereafter, the fuse holder, under the action of gravity, rotates clockwise to the position shown in Fig. 2. This has the effect of placing the flats 47 and 49 so that the gudgeons 43 and 45 may be moved flatwise up through the narrower slots 10 27 and laterally out of the slots 25 and finally out of the mouths 23. The holder may then be re-fused for re-application.

It will be seen that the relatively light spring 15 73 insures that the gudgeons 93 will hold clear 20 of the notches 103. However, under some design conditions, where the inertia of the cap 67 is proper, it is possible for the motion of the cap when once instigated by the action of the spring terminals 7 to move clear and to fall outwardly 25 before dropping back into position in the notches 103. However, the presence of the spring 73 insures that such a condition of dropping back will not occur.

In view of the above, it will be seen that the 25 several objects of the invention are achieved and other advantageous results attained.

As many changes could be made in the above constructions without departing from the scope of the invention, it is intended that all matter 30 contained in the above description or shown in the accompanying drawings shall be interpreted as illustrative and not in a limiting sense.

I claim:

1. A fuse comprising a fixed line terminal and 35 a movable line terminal spaced therefrom, said movable line terminal comprising a springing cantilever biased in a direction away from the fixed line terminal, a fuse holder, a fixed terminal-engaging element on one end of the fuse 40 holder having a rotary support on the fixed line terminal, a movable terminal-engaging element at the other end of the fuse holder, a fuse link in the holder connecting the fixed and movable terminal-engaging elements and holding them 45 relatively closely together, the parts being arranged so that upon rotation of the fuse holder with respect to the fixed line terminal, said movable terminal-engaging element will deflect the cantilever toward the fixed line terminal to tension the fuse link in the fuse holder.

2. A fuse comprising a fixed line terminal and 55 a movable line terminal spaced therefrom, said movable line terminal comprising a springing cantilever biased in a direction away from the fixed line terminal, a fuse holder, a fixed terminal-engaging element on one end of the fuse 60 holder having a rotary support on the fixed line terminal, a movable terminal-engaging element at the other end of the fuse holder, a fuse link 65 in the holder connecting the fixed and movable terminal-engaging elements and holding them relatively closely together, the parts being arranged so that upon rotation of the fuse holder with respect to the fixed line terminal, said movable terminal-engaging element will deflect the cantilever toward the fixed line terminal to tension the fuse link, the contact between the movable terminal-engaging element and said cantilever line terminal being substantially non-frictional, and the movement of the movable terminal-engaging element being such as to clear the biased position of the cantilever when the fuse 70 link is broken, whereby the fuse holder may thereafter rotate to an open position.

3. A fuse comprising a lower fixed line terminal, an upper springing cantilever line terminal which normally biases to assume a position relatively distant from the fixed line terminal, a 5 fuse holder, a lower fixed terminal-engaging element on the fuse holder attachable to and rotary with respect to the fixed line terminal, said fuse holder having an open lower end, an axially movable terminal-engaging element at 10 the upper end of the fuse holder, a fuse link connecting said terminal-engaging elements and holding them relatively closely together, the upper cantilever line terminal and the movable terminal-engaging element being related so that 15 when the fuse holder is rotated into closed-circuit position the cantilever is deflected to bias the movable terminal-engaging element upwardly and to tension the fuse link, the movement of the movable terminal-engaging element being 20 such as to clear the cantilever in its normal operating position when the fuse link separates.

4. A fuse comprising a lower fixed line terminal, an upper springing cantilever line terminal which normally biases to assume a position relatively distant from the fixed line terminal, a 25 fuse holder, a lower fixed terminal-engaging element on the fuse holder rotary with respect to the fixed line terminal, said fuse holder having an open lower end, an axially movable terminal-engaging element at the upper end of the fuse holder, a fuse link connecting said terminal-engaging elements and holding them relatively closely together, the upper cantilever line terminal and the movable terminal-engaging element 30 being related so that when the fuse holder is rotated into closed-circuit position the cantilever is deflected to bias the movable terminal-engaging element upwardly and to tension the fuse link, the movement of the movable terminal-engaging element being such as to clear the cantilever in its normal operating position when the fuse link separates, and spring means reacting 35 between the fuse holder and its movable terminal-engaging element to maintain the latter in maximum spaced relationship from the fixed terminal-engaging element after the fuse has 40 broken.

5. A fuse comprising a fixed line terminal, a springing cantilever line terminal having a cam end and an adjacent notch and normally biased to a position away from the fixed line terminal, a fuse holder, a fixed terminal-engaging element 5 on one end of the fuse holder rotary with respect to the fixed line terminal, an axially movable terminal-engaging element at the other end of the fuse holder, a fuse link joining the terminal-engaging elements to hold the movable engaging 10 element relatively near the fixed engaging element, means on the movable engaging element engageable with said cam end upon rotation of the fuse holder and cooperative with the notch in final position to deflect said cantilever toward 15 the fixed line terminal whereby the fuse link is tensioned, the movement of the movable terminal-engaging element being enough that when the fuse link separates and the cantilever line terminal biases the movable terminal-engaging 20 element said terminal-engaging element will clear the notch.

6. A fuse comprising a fixed line terminal, a springing cantilever line terminal having a cam end and an adjacent notch and normally biased 25 to a position away from the fixed line terminal, a fuse holder, a fixed terminal-engaging element on one end of the fuse holder rotary on the fixed line terminal, an axially movable terminal-engaging element at the other end of the fuse 30 holder, a fuse link joining the terminal-engaging elements to hold the movable engaging element relatively near the fixed engaging element, means on the movable engaging element engageable with said cam end upon rotation of the 35 fuse holder and cooperative with the notch in final position to deflect said cantilever toward the fixed line terminal whereby the fuse link is tensioned, the movement of the movable terminal-engaging element being enough that when 40 the fuse link separates and the cantilever line terminal biases the movable terminal-engaging element said terminal-engaging element may clear the notch, and a spring reacting between the fuse holder and the movable terminal-en- 45 gaging element to maintain said clearance.

THEODORE BIRKENMAIER.
